UNITED STATES PATENT OFFICE

ALFRED L. ADRIANSON, OF RACINE, WISCONSIN

MATERIAL TREATING APPARATUS

Application filed February 7, 1930. Serial No. 426,487.

My invention relates to machines for treating compost, foundry sand and other materials to effect a disintegration, loosening up and separation thereof into finely divided particles, and has reference more particularly to an improved screen structure which may be conveniently constructed in a portable form with operating power unit and provided with facilities for distributing or scattering the material onto the screen in a manner to insure a fine uniform product.

The principal objects of my invention are to provide an improved machine for comminuting and sifting compost, foundry sand and other materials; to effectively break up the material into small particles; to provide an improved screen structure; to insure a positive supply and distribution of the material onto the screen; to aerate the material; to utilize a resiliency supported or vibratable chute or carrier member in supplying the material to the screen; to provide a rotary member which co-operates with the chute or carrier to feed the material to the screen; to provide means which operates in conjunction with the resilient carrier to effect a thorough and fine comminution or breaking up of the material supplied to the screen; to construct the mechanism in a compact and convenient portable form; to provide for simultaneous operation of the comminuting or feeding and sifting mechanisms from a common power unit which is incorporated in the portable outfit; and in general to provide a simple, compact, convenient and inexpensive portable outfit of the character above referred to.

On the drawings:

Fig. 1 is a side elevation of a machine embodying my improvements and having a portion of the side wall broken away to show the screen mounting;

Fig. 2 is an end elevation of the machine;

Fig. 3 is a sectional view taken along the line 3—3 of Fig. 1;

Fig. 4 is a sectional view of part of the machine taken along the line 4—4 of Fig. 3, and

Fig. 5 is an enlarged sectional view taken along the line 5—5 of Fig. 4.

Fig. 6 is a side view, with parts broken away and in section, of the upper portion of

a similar machine having a modified form of mechanism for feeding the material to the screen;

Fig. 7 is a front view of the structure of Fig. 6 with portions broken away;

Fig. 8 is an enlarged view taken substantially on the line 8—8 of Fig. 6, and

Fig. 9 is an enlarged view taken substantially on the line 9—9 of Fig. 7.

Referring to the machine shown in Figs. 1 to 5 inclusive of the drawings, the reference numeral 1 indicates the frame of the machine which is supported on wheels 2 for portability and has rest legs 3 and a handle bar 4. The machine has a top or cover 5 and the upper portion of the machine is closed at the sides by the side panels or walls 6 and at the front by the plates 7 and 8, which support a hopper 9 which feeds through an opening 10 to the interior of the machine.

Within the main frame 1 is an auxiliary frame 70 which is supported at an inclination by a pair of coil springs 44 at the lower end and at the upper end by a pair of leaf springs 45 of substantially the form shown in Figs. 1 and 4 and arranged at opposite sides respectively of the auxiliary frame.

This auxiliary frame has the bottom 11, side walls 12 and upper end wall 46, but is open at the top and at the lower end. A pair of screens 13 and 14 are mounted in the auxiliary frame in superposed relation and each at a different inclination, the lower screen 13, which is of finer mesh than the upper screen 14, being at a more abrupt inclination which is necessary to keep the finer material moving along the lower screen 13 at a suitable rate to insure sufficient action. Spouts 16 and 17, which are oppositely inclined as shown in Fig. 2, are secured to the side walls 12 of the auxiliary frame at the lower ends respectively of the screens 13 and 14, to receive the deposit therefrom, and the bottom 11 which collects material falling through the lower screen 13, terminates above the lower end of the auxiliary frame in a downturned flange 18 which together with a plate 19, forms a discharge opening 20 between the sides of the machine.

The front plate 8 of the machine is preferably bent outwardly as shown to cover the spouts 100

16 and 17 and avoid spilling material therein as it is being supplied to the hopper 9.

For mounting the screens 13 and 14, each has the lower end clamped by bolts 47 between a pair of bars 48 which are somewhat longer than the width of the respective screens, and the ends of these bars are engaged in notches 49 in the side walls 12 of the auxiliary frame. The upper ends of the screens 13 and 14 are likewise clamped between similar bars 50, which, however, are substantially the same length as the width of the screens so as to fit between the side walls 12 and each pair of bars 50 is secured to a pair of bolts 51 which extend through the end wall 46 of the auxiliary frame and are provided with nuts 52 which serve to stretch the screens 13 and 14 taut and to hold the lower end bars 48 in the notches 49.

To prevent the screens 13 and 14 from whipping and breaking under the vibratory action of the screen structure, a plurality of spacer rods or pipes 15 extend between the side walls 12 and are arranged at suitable intervals between the upper and lower ends of the screens 13 and 14 and slightly above the normal plane thereof so that the screen cloth is drawn tightly thereover somewhat as shown in Fig. 4 and the spacer rods or pipes 15 thus prevent whipping and breaking of the screen cloth which would otherwise occur.

Mounted on the frame 1 above the screens 13 and 14, is a compartment 21 having end walls 22 and 23, side walls 24 and a top wall 35 53, and this compartment opens at the bottom onto the upper screen 14. A rotary member 27, which may be in the form of a brush or otherwise, depending upon the material to be operated upon, is mounted at the front of the compartment 21 so as to project under the wall 23, said brush being of substantially the same length as the width between the side walls 24 of the compartment, and this rotary member is arranged and operated in the proper direction indicated by the arrow in Fig. 4, so as to sweep material from the hopper 9 into the compartment 21 so that the material is not only broken up into particles by the operation of the rotary member, but is thrown about in the compartment and aerated by the spraying or distributing action of the rotary member 27.

The side walls 24 of the compartment 21 extend forwardly along the ends of the brush 55 27 to the hopper so as to form a passageway therebetween and the bottom of this passageway consists of a plate or carrier member 29 which is hingedly mounted on a shaft 30 so as to swing to and from the brush member 27. Said plate 29 is held in adjustable relation to the brush 27, by an arm 31 rigidly secured to the shaft 30 and having a link 32 on the outer end extending loosely through a bracket 33, which is secured to the side wall 6 of the machine, said link 32 being provided with a

spring 42 thereon which is compressed between the bracket 33 and a wing nut 43 to exert a lifting tension on the arm 31 and hold the bottom or plate 29 resiliently against the periphery of the brush 27.

The auxiliary screen frame is provided at its under side with bearings 34 for a shaft 35 which has eccentric weights 36 and a pulley 37 secured to it, and this pulley 37 is connected by the belt 41 with a drive pulley of a motor 40 which is mounted on the frame of the machine under the inclined screen frame. The shaft 28 of the brush 27 also has a pulley 38 thereon which is driven by the belt 39 from a driving pulley of the motor 40 so that the brush 27 is rotated as the auxiliary screen frame is vibrated.

In the operation of the machine, the material to be pulverized, aerated and sifted is put into the hopper 9 and the motor 40 is started. The material falling upon the plate 29 will be swept into the compartment 21, being at the same time pulverized by the action of the brush 27, thrown about in the compartment 21 and finally deposited on the screen 14. The rotation of the shaft 35 carrying the eccentric weights 36, causes the screen frame to oscillate and vibrate and a rapid and efficient sifting action will result. The coarse material not going through the screens 14 and 13, will be disposed of through chutes 17 and 16 respectively and the finer material will be dropped out through the opening 20.

Referring now to the structure shown in Figs. 6 to 9 inclusive, the machine is substantially the same as that previously described except that a vibratory chute is substituted in place of the hopper 9, brush 27 and resilient bottom plate 29. In this modified structure, the top or cover 54 of the machine is elevated somewhat at the forward end to accommodate a chute 55 through which material is delivered to the upper end of the vibratory screen frame, said chute being resiliently mounted and connected with the vibratory screen frame to have a vibratory movement imparted thereto. To this end, the forward end of the chute 55 is provided with a pair of bolts 56 which pass downwardly through apertures in a cross member 57 and each bolt is provided with springs 58 and 59 above and below the member 57 and held thereon by the nut 60 and washer 61.

The lower end of the chute 55 has a cross rod 62 secured thereon and provided at each end with a rubber ball 63 and each ball rests on the outturned flange of a bracket 64 on the side wall 12 of the screen frame. A spring 65 is connected at its upper end of the shaft 62 and at its lower end to an adjusting bolt 66 which engages through an aperture of a bracket 67 on the side wall 12 of the screen 130

frame for holding the rubber ball 63 against the bracket plate 64.

The screen frame 70 of the structure of Figs. 6 to 9 inclusive, is the same as and vibrated in the same manner as the screen structure of the preceding figures and the vibratory movement of the screen frame is transmitted to the chute 55. To prevent spilling the material as it is being supplied to the chute 55, a cover member 68 is provided having side walls 69 which extend down close to the sides of the chute 55.

While I have shown and described my invention in a preferred form, I am aware that various changes and modifications may be made without departing from the principles of my invention, the scope of which is to be determined by the appended claims.

I claim as my invention:

1. In a machine of the class described the combination of a frame, an inclined screen resiliently mounted on the frame, a hopper in front of and spaced horizontally from the upper end of the screen, a rotary feed member at the side of the hopper and between the latter and the upper end of the screen for feeding material laterally from the hopper to the upper end portion of the screen, and a resiliently mounted guide extending from the hopper under and in proximity to the periphery of the rotary feed member.

2. In a machine of the class described the combination of a frame, an inclined screen resiliently mounted on the frame, a hopper in front of and spaced horizontally from the upper end of the screen, a rotary brush at the side of the hopper and between the latter and the upper end of the screen for feeding material laterally from the hopper to the upper end portion of the screen, and a resiliently mounted guide extending from the hopper under and in proximity to the periphery of the rotary feed member.

3. In a machine of the class described the combination of a frame, an inclined screen resiliently mounted on the frame, a hopper in front of and spaced from the upper end of the screen, a rotary feed member at the side of the hopper and between the latter and the upper end of the screen for feeding material from the hopper to the screen, and a partition separating substantially the upper half of the rotary feed member from the hopper compartment.

4. In a machine of the class described the combination of a frame provided with a pair of laterally spaced compartments, one of which is open at the top and the other of which is open at the bottom, a rotary feed member between the compartments and operable to feed material from the open top compartment to the open bottom compartment, a resiliently mounted guard at the under side of and co-operating with the rotary feed member to direct material from

the open top compartment upwardly in the open bottom compartment, and an inclined screen resiliently mounted on the frame in position to receive material from the open bottom compartment on the upper end portion of the screen.
